229,568

SAFETY ENCLOSURE FOR YOUNG FISH

Allan H. Willinger, New Rochelle, N.Y., assignor to
Metaframe Corporation, Maywood, N.J.

Filed Apr. 6, 1972, Ser. No. 241,881

Term of patent 14 years

Int. Cl. D30—02

U.S. Cl. D30—6

FIG. 1.

FIG. 2.

FIG. 3.

FIG. 4.

FIG. 5.

FIG. 1 is a top plan view of the safety enclosure for young fish showing my new design;

FIG. 2 is a bottom plan view thereof;

FIG. 3 is an elevational view of one side thereof, the opposite side thereof being identical;

FIG. 4 is an elevational view of the front thereof, the back thereof being identical; and

FIG. 5 is a side cross-sectional view thereof.

I claim:

The ornamental design for a safety enclosure for young fish, substantially as shown and described.
